UNITED STATES PATENT OFFICE.

BIAGIO MARTINI, OF PITTSBURGH, PENNSYLVANIA.

GUIDE FOR RAIL-CUTTING TORCHES.

Application filed July 19, 1927. Serial No. 206,885.

This invention relates to guides for cutting-torches used in particular for cutting railway-rails.

The primary object of this invention is to provide a guide for a rail cutting-torch which may be readily mounted on a rail and which can be used on various sizes of rails. Another object of this invention is to provide such a guide and support in which the cutting-torch may be mounted or removed with great ease. A further object is to provide such a guide which permits of the cutting of a rail, or the like, by means of a torch in a practically straight cut which requires no further finishing and whereby the cutting operation proper may be performed with one hand only. Still a further object is the provision of a guide of this character wherein the cutting-torch may be adjusted angularly to suit the best working conditions. Yet another object is to produce a device of the purpose stated above which is simple in construction and operation, sufficiently light in weight to be easily carried about by a workman and which can be manufactured at relatively low cost. Additional features and advantages of this invention will appear from the following description considered in connection with the accompanying drawings forming a part of this application, and in which:

Fig. 1 is a side elevation showing the device applied to a railroad-rail.

Fig. 2 is a top plan view of Fig. 1.

Fig. 3 is a front elevation of Fig. 1.

Fig. 4 is a detail view of the torch-holding-arm.

Fig. 5 is a perspective view of a latch used for holding in place the torch-holding-arm.

Figs. 6 and 7 are fragmentary and diagrammatic views illustrating the operation of the device.

Reference being had to the drawings, the device comprises a supporting frame made up of the two identical frame-plates 1 and 2 held in suitable spaced and parallel relation by means of the through-bolts 3 engaging the spacing-tubes 4. The forward sides of these frame-plates are cut out to produce the rail-supports 5, the upper clamping-arms 6 and the intermediate extensions 7 which are adapted to bear against the web 8 of the rail 9, indicated in dot and dash lines in Fig. 1. Fastened to and between the clamping arms by means of the screws 10 is the bridge-member 11, the mid-

dle portion 12 of which is enlarged and threaded to receive a clamping screw 13, of any desired and suitable type.

Rockably mounted on the two frame-plates is the lever-shaft 14 having at one end a square portion 15 upon which is mounted the suitably curved lever 16 which is held in place by means of a washer 17 and a nut 18, screwed on the threaded extension 19 of the shaft. At its upper end the lever has a head 20 in which is driven a sleeve member 21 of steel or other wear resisting material.

Rockably connected to the lever is the torch-holding-arm 22 at the upper end of which is secured a pin 23 adapted to rotate within the sleeve member 21. This pin has an enlarged portion 24 in which is turned a circular groove 25, the purpose of which will be stated hereafter. The lower end of the arm 22 is enlarged and to it is adjustably secured, by means of the machine-screw 26, the inner torch clamping disc 27. The latter is provided with a diametral groove 28 of ample width and depth to accommodate the various pipes 29 of the cutting torch 30, which may be of any standard type now available in the trade. These pipes are clamped in proper position on the torch arm by means of the outer clamping disc 31 which is substantially similar to the inner disc and which is held thereon by the clamping screws 32.

The torch-holding-arm 22 is preferably held in place on the lever 16 by means of a latch 33 which is rockably mounted on the lever-head 20. In this latch is cut a slot 34 which is adapted to engage the groove 25 in the pin 23 and which, therefore, prevents the torch-holding-arm from shifting in the lever during the manipulation of the cutting-torch.

Placed around the shaft 14 is a coil spring 35 one end of which is secured to the shaft at 36 whereas the other end is held in a hole 100 or slot 37 provided in the frame-plate 2. This spring is preferably protected against rain and the flying particles of molten metal by a tubular casing 38. The tendency of this spring is to rotate the lever 16 in a counter-clock-wise direction, as shown by the arrow 39 in Fig. 1. This rotation is limited by the stop-pin 40 which allows the lever to assume the substantially vertical position shown in said Fig. 1.

In order to protect the operator from the flying sparks of molten metal, a shield 41

may be mounted, at the desired angle, on the frame-plate 1. This shield is secured thereon by means of an angle-iron 42 which is fastened on the frame by screws 43. A slot 44 is cut in the lower end of the shield to accommodate the lever 16 and to form a stop to the forward rotation of the latter. When this shield is used, the stop-pin 40 may, of course, be dispensed with.

10 The clockwise rotation of the torch-holding-arm 22 on the lever 16 is limited to the proper amount by the stop-lug 45 provided on said lever.

15 From the above description, the operation of my device will be readily understood and may be briefly stated to be as follows:

Assuming that one end of the rail 9 (Fig. 1) is to be cut away, the frame is suitably located on the rail and secured thereon by the 20 clamping-screw 13. Next, the torch 30 is properly adjusted as to height and angle on the torch-holding-arm 22 by means of the clamping screws 32 and the machine-screw 26, so that the flame from the torch may 25 traverse the whole section of the rail. The operator now ignites the torch and, holding the same by one hand only, rotates it in a clockwise direction using the pin 23 as a fulcrum. When the torch assumes substantially the position shown in Fig. 6, the flame will have cut through the whole base of the rail and a portion of the web thereof, and the torch-holding-arm will strike the stop-lug 45. From now on, the center of rotation of 30 the torch will change from the pin 23 to the shaft 14 and the remaining portion of the rail-web and the rail-head will be cut through. Any upwardly flying sparks will be arrested by the shield 41.

40 It will be observed that by rotating the torch about two fulcrums disposed as shown in the drawings, the tip 46 of the torch will first move toward the rail and then away therefrom, describing the two arcs 47 and 48 shown in Fig. 6. By this arrangement, the torch-tip is brought very close to the object to be cut, so that the flame is used to the best advantage.

45 After the rail is cut through, the operator releases the torch, and the latter reverts back to the normal position shown in Fig. 1 owing to the retractile action of the spring 35.

50 While I have described my invention as applied to the cutting of rails, it will be readily understood that by slightly modifying some of the proportions of the various parts, it may be used for cutting many kinds of structural steel shapes. Also, I reserve the right of making all such changes found 55 desirable and as fall within the scope of the appended claims.

I claim:

1. In a guide for a torch for cutting rails and the like, rockable torch guiding means 60 adapted to rotate the torch successively about

two fulcrums during the cutting operation.

2. In a guide for a torch for cutting rails and the like, the combination of a frame; means for securing the frame to the rail to be cut, and rockable torch holding means 70 mounted on the frame and adapted to guide said torch for rotation successively about two fulcrums during the cutting operation.

3. In a guide for a torch for cutting rails and the like, the combination of a frame; 75 means for removably securing the same to the rail to be cut; rockable torch holding means mounted on said frame and adapted to guide said torch for rotation successively about two fulcrums during the cutting operation, and 80 self-actuating means for returning said torch into inoperative position.

4. In a guide for a torch for cutting rails and the like, the combination of a frame; 85 means for removably securing the same to the rail to be cut; rockable torch holding means mounted on said frame and adapted to guide said torch for rotation successively about two fulcrums during the cutting operation, and means for limiting the rotation 90 of the torch about the first fulcrum.

5. In a guide for a torch for cutting rails and the like, the combination of a frame; means for removably securing the same to the rail to be cut; rockable torch holding means mounted on said frame and adapted to guide said torch for rotation successively about two fulcrums during the cutting operation, and means for limiting the rotation 100 in one direction of the torch about the second fulcrum.

6. In a guide for a torch for cutting rails and the like, the combination of a frame; means for securing said frame to the rail to be cut; a lever pivotally mounted on the 105 frame; an arm pivotally mounted on said lever, and means for limiting the rotation in one direction of said lever.

7. In a guide for a torch for cutting rails and the like, the combination of a frame; 110 means for securing said frame to the rail to be cut; a lever pivotally mounted on the frame; an arm pivotally mounted on said lever, and means for limiting the rotation of said arm on said lever.

8. In a guide for a torch for cutting rails and the like, the combination of a frame; means for securing said frame to the rail to be cut; a lever pivotally mounted on the frame; an arm pivotally mounted on said lever, and self-actuating means for returning 115 said lever into original position.

9. In a guide for a torch for cutting rails and the like, the combination of a frame; means for removably securing the same to the object to be cut; rockable torch holding means mounted on said frame and adapted to guide said torch for rotation successively about two fulcrums during the cutting operation; self-actuating means for returning 120 125 130

the torch holding means into inoperative position and means for limiting said return motion.

10. In a guide for a torch for cutting rails and the like, the combination of a frame; means for removably securing the same to the object to be cut; rockable torch holding means mounted on said frame and adapted to guide said torch for rotation successively about two fulcrums during the cutting operation; self-actuating means for returning the torch holding means into inoperative position, and means positioned on said frame for limiting said return motion.
- 15 11. In a guide for a torch for cutting rails and the like, the combination of a frame; means for removably securing the same to the object to be cut; rockable torch holding

means mounted on said frame and adapted to guide said torch for rotation successively about two fulcrums during the cutting operation; self-actuating means for returning the torch holding means into inoperative position, and means positioned on said frame for limiting said return motion.

20 25 12. In a guide for a torch for cutting rails and the like, the combination of a frame; means for securing said frame to the object to be cut; a lever pivotally mounted on the frame; an arm pivotally mounted on said lever, and stopping means positioned on said lever to limit the rotation of said arm thereon.

In testimony whereof I affix my signature.

BIAGIO MARTINI.
